UNITED STATES PATENT OFFICE.

JOHN HOPSON, JR., OF NEW LONDON, ASSIGNOR TO THE WATERBURY CLOCK COMPANY, OF WATERBURY, CONNECTICUT.

DESIGN FOR A CLOCK-CASE.

SPECIFICATION forming part of Design No. 23,696, dated October 16, 1894.

Application filed September 7, 1894. Serial No. 522,398. Term of patent 7 years.

To all whom it may concern:

Be it known that I, JOHN HOPSON, Jr., of New London, in the county of New London and State of Connecticut, have invented a new 5 Design for Clock-Cases; and I do hereby declare the following, when taken in connection with the accompanying drawings and the letters of reference marked thereon, to be a full, clear, and exact description of the same, and 10 which said drawings constitute part of this specification, and represent, in—

Figure 1, a view in front elevation of a clock-case embodying my design; Fig. 2, a view thereof in side elevation.

15 My invention relates to a design for clock cases, and consists in the configuration and ornamentation hereinafter described and shown in the accompanying illustration.

20 My newly designed clock-case is pyramidal in general form, though not strictly so. Its front plate A has a central opening B for a dial, and is flanked on each side by two long, highly ornate, composite scrolls C, the lower ends of which form rounded feet C'. Between 25 these feet there is a drapery D, composed of freely treated scroll and leaf-like forms. Between the upper ends of the side scrolls C there is an arched scroll E, provided

at its center with a shell E', having a flamboyant leaf-like crest E². Below the shell and 30 over the dial opening B there is a garland F of flowers. Between the side scrolls C and the dial-opening B I locate corresponding, very irregular panels G, containing flowers G'. I have thus described the aspect of the front 35 of the case, which projects beyond the body or main portion thereof, as shown by Fig. 2 of the drawings, the said body consisting of two corresponding side sections H, one of which is shown in Fig. 2, and a top section I, 40 and a back section, of which only the feet I' are displayed. Each of the side-sections and the top-section has a conventional border J, and each contains an oblong panel K, inclosing sprays L of flowers. 45

I claim—

The design for a clock case, as herein described and shown.

In testimony whereof I have signed this specification in the presence of two subscr- 50 ing witnesses.

JOHN HOPSON, JR.
